UNITED STATES PATENT OFFICE.

PARKER H. SWEET, JR., OF WASHINGTON, DISTRICT OF COLUMBIA.

MACHINE FOR ATTACHING BUTTONS TO SHOES.

SPECIFICATION forming part of Letters Patent No. 268,143, dated November 28, 1882.

Application filed September 19, 1882. (No model.)

To all whom it may concern:

Be it known that I, PARKER H. SWEET, Jr., a citizen of the United States, residing at Washington, in the District of Columbia, have invented certain new and useful Improvements 5 in Machines for Attaching Buttons to Shoes or other Articles; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention has for its object to provide an improved machine for automatically attaching buttons to shoes or to other articles of wearing-apparel by means of a metallic tack or other suitable metallic fastening device; and 20 my improvements consist essentially of a supporting-frame provided with a vertical plunger operated by a series of levers through the medium of a foot-treadle or other suitable power, the said plunger being provided with a holding-jaw for receiving the metallic fastener preparatory to connecting the button to a fabric therewith, as will be hereinafter described.

It also consists of an improved means for automatically feeding both the buttons and the 30 metallic fasteners into position to be attached to the desired material.

It further consists of other details of construction and general arrangement of parts, all 35 as will be hereinafter more fully described, and specifically designated in the claims.

In the accompanying drawings, Figure 1 represents a side elevation of my improved machine, with parts broken away to more fully show its construction. Fig. 2 represents a detail 40 sectional view of the hopper for distributing the buttons. Fig. 3 represents a top plan view of the hopper for distributing the metallic fasteners. Fig. 4 represents a vertical section of the same. Fig. 5 represents a vertical 45 section of the recess for holding the button, with the concave die for deflecting the prong or prongs of the fastening device through the shank of the button to attach it to the desired material. Figs. 6 and 7 represent detail sectional views of the inclined conducting-chutes 50 for the buttons and metallic fasteners.

Similar letters of reference occurring on the several figures indicate corresponding parts.

Referring to the drawings, A represents the base of my improved machine, which is provided with a curved arm, A', terminating in a hollow cylindrical support, A², which is adapted to receive the vertically-sliding plunger B, as fully shown in Fig. 1.

Projecting upward from the curved arm A', 60 and cast solid therewith, is an upright, A³, in the upper part of which is pivoted a horizontal lever, B', to the front end of which is pivoted the upper end of the vertical plunger B, while the rear end of the said lever is slotted 65 for the engagement therewith of the pin a of the elbow-lever C, which is pivoted in its turn, at its center, to a projection, D, at the rear of the base-plate A. To the outer end of this elbow-lever C is pivoted a pitman or rod, E, 70 which is connected at its bottom to a suitable treadle for operating the machine.

F represents an inclined chute or conductor, which passes through a recess, b, in the arm A', and which is pivoted at one end near the front of the base A, as shown at c, while its rear end abuts against the lower end of the casing of the distributing-wheel G in such a manner as to receive the buttons as they are ejected from the same. The hopper H is of 80 the usual form and mounted upon a cylindrical case, H', which in turn is mounted upon the projection D at the rear of the base A.

Within the walls of the cylindrical case H' is journaled the distributing-wheel G by means 85 of the axle d, a space or recess, e, being provided to one side and at the bottom, between said wheel and case, for the passage of the button-heads, as fully shown in Fig. 2 of the drawings.

Upon the face of the wheel, and at suitable 90 distances apart, are provided slots or recesses f for the reception of the shanks of the buttons, to permit the button-heads to pass through the opening g down into the space or recess e. 95 At the extreme lower part of the said recess, and beneath the wheel G, is provided a rod, h, which projects through the casing H' and abuts against the button at the bottom of the said recess to eject or push it outward into the 100 conducting-chute F, said rod being pivoted to one end of the lever K, which is also pivoted

at its center to the projection D in the rear of the machine, a suitable rod, *i*, connecting said lever with the elbow-lever C to derive the desired motion.

5 Upon the outer end of the axle *d*, carrying the distributing-wheel G, is arranged a ratchet-wheel, *d'*, the teeth of which engage with the stationary pawl *d''* upon the elbow-lever C to impart motion to the said wheel G, the ends of 10 the axle *d* being journaled in the projection D, and a projection, D', of the main frame of the machine, as fully shown in Fig. 1.

The conducting-chute F is preferably of a circular form in cross-section, with a slot, *f'*, 15 in its upper surface for the reception of the shanks of the buttons, to keep the same in proper position to receive the prong or prongs of the metallic fastener, the lower end of the said chute connecting with a circular recess or 20 cavity, *a'*, in the base A of the machine, and which extends to and opens out at the front of the same. The upper part of this recess *a'* is provided with a slot, *f''*, terminating on its 25 upper surface with a concaved groove or die, *f'''*, to curve or deflect the point of the metallic fastener held in the jaw of the plunger B down through the shank of the button, as fully shown in Fig. 5.

In the lower part of the recess or cavity *a'*, 30 near the front of the base A, is provided an opening, *k*, which is adapted to receive a curved spring, *l*, to hold the first and each succeeding button as it slides down from the chute F in a position to receive the prong of the setting 35 device.

M represents an inclined conductor or chute for supplying the metallic tacks or fasteners to the holding-jaw of the plunger B, said conductor being of a shape similar to that of the 40 chute F, with the exception that the groove or slot *f⁴* is in the lower part of the same, instead of at the top, to allow of the points of the metallic tacks or fasteners to project downward, as shown. The lower part of the plunger, constituting the holding-jaw, is preferably provided 45 with a magnet, *m*, to hold the iron or steel tack in position to be affixed to the shank of the button in the recess *a'* directly beneath; but where the fastening device is made of other metals a slot, *a²*, may be formed in the lower part of the plunger B to receive the same; or any of the well-known forms of holding-jaw may be used. The upper end of this 50 chute or conductor M projects against the mouth of a distributing-hopper, L, which feeds the metallic tacks or fasteners down through said chute to the holding-jaw of the plunger B. The distributing-hopper L is composed of a suitable frame, open at the top and provided 55 with a slotted and inclined tray, *n*, arranged horizontally across said frame at or about its center. The slots *o*, which extend through the said tray, terminate in a single slot in the end of the tray, for distributing the tacks one after another into the conducting-chute M, a partition or beard, N, extending across the said tray

at such a height above the same as to leave only a space sufficient to allow the heads of the tacks to pass under after the points of the tacks have dropped downward in the slots. This hopper 70 L is attached to the top of a standard, *p*, which is pivoted at its bottom to a projecting lug on the curved arm A', and a lug or pin, *q*, projecting from the side of the said hopper engages with the curve of the elbow-lever C to impart a slight shaking motion to the same, so that the points of the metallic tacks will project down through the slots *o* in the tray *n* for distribution to the conductor M. A recess or 75 opening, *s*, is provided in the upper surface of this conductor, near the plunger B, to permit of the entrance of the finger *t* of the lever *v*, which is pivoted to the arm A' and operated by the rod *w*, pivoted thereto and to the lever B', as fully shown in Fig. 1. The object of 80 this mechanism is such that the metallic tacks are pushed one after another upon the holding-jaw of the plunger B with each successive motion of the lever B'. A suitable coiled spring, P, is arranged between the curved arm A' and the lever B', to force the plunger B back to its proper position after each downward stroke of 85 the same. The conducting-chutes F and M, with their distributing-hoppers, may be changed or reversed, so that the buttons may be fed down to the holding-jaw of the plunger B and the metallic tacks or fasteners down to the recess in the base of the machine, directly under said plunger, without departing from the spirit of 90 my invention.

In the operation of my improved machine the buttons are thrown loosely into the hopper H, from which they are distributed in proper position to the chute F by means of the distributing-wheel G, while the tacks or fasteners are assorted in the hopper L and fed down the inclined chute M, the finger *t* of the lever *v* pushing the first and each succeeding tack upon the holding-jaw *m* of the plunger B with each upward motion of the said plunger. The 95 material or fabric to which the button is to be attached is placed upon the table of the base A directly over the first button, near the outer end of the recess *a'* of the said base A. The plunger B, carrying the metallic tack or fastener, is now brought down by depressing the foot-treadle, which operation causes the point of the metallic tack to pass through the said material or fabric down into the concave die *f'''*, where it is curved or deflected through the 100 shank of the button, and back upon or into the material, thereby firmly securing the button thereto. Now, by pulling the material forward, the button depresses the spring *l* in the groove *k* and allows the button to easily slip out of the recess *a'*. The next succeeding button now slips down against the spring, and as the plunger B returns to its former position the finger *t* of the lever *v* pushes another metallic tack in place to set the next button, and 105 this operation is repeated until the supply of buttons and fasteners is exhausted.

Having thus described my invention, what I claim as new and useful is—

1. An automatic machine for attaching buttons to fabrics, consisting of a supporting-frame provided with a plunger, B, having a suitable holding-jaw, and operated by a series of levers connecting with a foot-treadle or other suitable power, and hoppers for distributing the buttons and metallic fasteners to inclined 5 conductors, all substantially as shown and described, whereby the said buttons and fasteners are fed into position from separate conductors, one after the other, for attachment to the desired material, substantially as and for 10 the purpose specified.
2. In a machine for attaching buttons to fabrics, the inclined conductors F and M, provided respectively with the hoppers H and L and their feed mechanisms, in combination with 15 the plunger B, having a holding-jaw, m, and the recess a' in the base of said frame, substantially as and for the purpose specified.

3. The hopper H, mounted upon the cylindrical casing H', and provided with the distributing-wheel G, having slots f and central axle, d, a space, e, being provided to one side and at the bottom of said wheel and casing, in combination with the inclined conductor F, projections D D', rod h, lever K, connecting-rod i, ratchet-wheel d', and pawl d'', substantially as and for the purpose specified. 25

4. The hopper L, provided with the tray n, having vertical slots or openings o, and partition N, in combination with the inclined conductor M, substantially as and for the purpose 30 specified. 35

In testimony whereof I affix my signature in presence of two witnesses.
